TOY

Neil C. Stilwell, Anderson, Ind.

Application November 30, 1934, Serial No. 755,269

6 Claims. (Cl. 46—11)

The object of my invention is to produce an article which may be readily associated with cartons, such for instance as butter and lard cartons, shoe boxes and the like, by means of which such cartons may be readily formed into a draggable toy and an indefinite number thereof associated in series to form a train.

The accompanying drawing illustrates my invention.

10 Fig. 1 is a side elevation in partial vertical section of such a carton equipped with a pair of my improved articles;

Fig. 2 is an end elevation;

15 Fig. 3 is a vertical section, on a larger scale, showing a fragment of such a carton equipped with one form of my device arranged within the carton;

Fig. 4 is a view similar to Fig. 3 showing the same form of my article arranged with the main body thereof on the exterior of the carton;

20 Fig. 5 is a fragmentary vertical section on line 5—5 of Fig. 4;

Fig. 6 is a horizontal section on line 6—6 of Fig. 5;

25 Fig. 7 is a perspective view of one form of my device;

Fig. 8 is a perspective view of another form;

Fig. 9 is a plan on a larger scale showing the manner in which two such articles may be coupled 30 together; and

Fig. 10 is a plan of a paper blank showing the manner in which my improved article may be produced from material which is commonly wasted in the production of a carton with which 35 my device may be associated.

In the drawing, 10 indicates the main body of my improved article, which may be formed of any suitable sheet material such as cardboard or thin metal. The opposite sides of the body 10 are provided with wheel simulating portions 11, 11 foldable, on the fold lines 12, 12, to positions at right angles to the main body 10. Integral with each ear 11, upon the opposite side of the fold line, is a tongue 13 struck out from the main body 40 10 and a portion 13' of this tongue, severed from ear 11 along the line 14 may be turned, on the fold line 15, to a position substantially at right angles to tongue 13. The upper edges 16 of tongue 13 and tongue supplement 13' may be inclined relative to each other, as shown at the left-hand end of Fig. 7, to facilitate penetration 45 of a carton, or may be left as shown at the right-hand end of Fig. 7. Projecting from one end of main body 10 is a coupling tongue 17 provided at 50 one side edge with an open ended inclined slot 18,

this construction being such that the two sets of tongues 17 may be coupled together, as shown in Fig. 9, the coupling being such as to permit relative swing of two coupled plates.

It will be readily understood that various modifications of the structure illustrated in Fig. 7 may be made without departing from the spirit of my invention. For instance, in Fig. 8, the main body 10' is only provided with wheel simulating ears 11 and tongue 17. It will be also readily understood that means other than the open ended slot 18 may be provided to facilitate coupling without departing from the spirit of my invention.

The carton 20, in the drawing, is illustrated as of a common type used to contain butter, lard, etc., but it will be readily understood that the details of construction form no part of my invention. If the cartons are intended by the distributor to be subsequently used in conjunction with my devices the bottoms 21 thereof may be provided with markings, weakened portions, or perforations 22 to facilitate association of my devices therewith.

In order to associate the device shown in Fig. 7 with a carton, the device may either be inserted in the carton and ears 11 projected outwardly through the bottom of the carton, and tongue 17 projected outwardly through or beneath an end wall of the carton as shown in Fig. 3 or tongues 30 13 may be projected inwardly through the bottom as shown in Fig. 4. When ears 11 are projected outwardly through the bottom the tongue supplements 13' may be turned at right angles to tongues 13 so that their lower edges will engage 35 the bottom of the carton at a substantial angle to the tongue 13, thereby bracing the structure, as shown in Fig. 6. If the structure shown in Fig. 7 has had its tongues 13 projected inwardly 40 through the bottom of the carton such projection may be accomplished either while tongue supplement 13' is in the same plane as tongue 13 and tongue supplement 13' then swung to a position at an angle to tongue 13 over the bottom of the carton, or the tongue supplement 13' may be first 45 swung to a position at an angle to tongue 13 and penetration of the bottom of the carton then accomplished, the tongue supplement 13' being thereafter swung over the upper face of the bottom of the carton, as shown in Fig. 6, if desired. 50

The form shown in Fig. 8 must have its main body arranged within the carton, the ears 11 being projected outwardly through the bottom of the carton and tongue 17 projected through or beneath the end of the carton, the forward edge 10' 55

of the main body being preferably closely adjacent the inner face of the end wall of the carton, as shown in Fig. 3.

It will be noted, from Fig. 10, that devices of such character may be readily formed, if desired, from material which is otherwise wasted in the production of the carton.

The width of the main body of my article, between the fold lines 12, may be equal to or less than the internal width of the carton with which my device is to be associated, but these dimensions are preferably equal, in the form shown in Fig. 7, so that the tongues 13 may serve to brace the wheel simulating ears 11 by engagement with the inner face of the adjacent side wall of the carton, as shown in Figs. 5 and 6.

It will be readily understood that a distributor of cartoned merchandise may readily estimate the proportion of his merchandise which will ultimately reach families having children and may therefore supply his distributors with an adequate number of my devices to enable those children to utilize his carton for toy purposes after the merchandise has been removed and that such a distributor, if he desires to stimulate his trade by an especial appeal to children, may decorate cartons to simulate toys and may, if he desires, so decorate them as to facilitate removal or displacement of portions thereof to further the modification of the cartons into simulations of various vehicles and other articles.

My structure is of such character that a pair of them may be readily enclosed with the merchandise, the space and size of such articles being such as to permit such enclosure without distortion of the carton and without substantially lessening the container value thereof.

A notch 25 may be formed at the root of tongue 13 so that, upon carton penetration, a slight vertical interlock will be formed.

I claim as my invention:

1. As an article of manufacture, a toy forming supplement for cartons comprising a main body sheet adapted to lie parallel to a bottom wall of a carton and having side ears bendable into

substantially vertical planes substantially at right angles to the horizontal plane of the main body, and a coupling tongue projecting from one end.

2. The combination with a shipping carton made up wholly of plane surfaces, each of said plane surfaces meeting each adjacent plane surface in a right angle, of a plate having a pair of portions at opposite sides lying substantially at right angles to the main body of the plate and projected through a wall of the carton, and having at one end a coupling tongue projecting beyond an end of the carton.

3. A shipping carton adapted to be converted into a toy by the attachment thereto of a plate having at opposite sides portions lying in planes substantially at right angles to the plane of the intermediate part of the plate and projecting beyond said plane in opposite directions and portions thereof projected through a wall of the carton, and also having at one end a projecting coupling tongue.

4. A structure of the character specified in the immediately preceding claim wherein each of the side portions of the plate is provided with a tongue supplement swingable to a position at a substantial angle to the main body of the tongue.

5. A truly rectangular carton which is convertible into a toy upon association therewith of a toy-forming supplement, comprising a main body sheet adapted to lie parallel to a bottom wall of a carton and having side ears bendable into substantially vertical planes substantially at right angles to the horizontal plane of the main body, and a coupling tongue projecting from one end.

6. A truly rectangular carton which is convertible into a toy upon association therewith of a toy-forming supplement, comprising a main body sheet having side ears bendable substantially at right angles to the plane of the main body, a pair of tongues projectable from the main body in a direction opposite to the direction of ear projection, and a pair of supplemental tongues of like character and positionable in planes at substantial angles to the planes of adjacent tongues.

NEIL C. STILWELL.
